METHOD AND APPARATUS FOR
TREATING CLAYSDavid G. Brandt, Westfield, N. J., assignor to
Doherty Research Company, New York, N. Y.,
a corporation of Delaware

Application March 17, 1934, Serial No. 716,056

6 Claims. (Cl. 252—2)

This invention relates to the revivification of contact filtering or decolorizing agents such as fuller's earth, bauxite, charcoal, metal oxides and other decolorizing agents used for the refining of mineral and vegetable oils. More particularly the invention relates to a process and apparatus for revivifying or reactivating pulverized clays or other contact materials used for refining petroleum oils.

10 Granular clays and filtering agents through which oils are percolated may be revivified in the usual type of multiple hearth furnace, but such processes are not entirely satisfactory even for cause clays. Certain other processes have been developed for washing fine clay on filters with various solvent agents and steaming has been resorted to for the purpose of partially revivifying and cleaning clays. However, no satisfactory process has been developed which will completely 20 revivify or reactivate clays or other treating materials particularly where they have a fineness in the neighborhood of 200 mesh.

25 The important object therefore of the present invention is to devise a process by which contact clays and treating agents may be completely reactivated or revivified for reuse.

A further object of the invention is the provision of a novel apparatus particularly adapted for carrying out this process.

30 In general the process comprises the steps of drying the filtering agent, mixing a regulated stream or quantity of the dried filtering agent to be revivified with a stream of a hot carrier gas, conducting the resulting mixture through a heating zone, and supplying sufficient oxygen to the mixture at various points during its travel through the heating zone to carry out the revivification and reoxidation of the agent without permitting an abnormal rise in temperature. 35 After the clay or filtering agent has been revivified, it is separated from the carrier gas and at least a portion of this gas is recirculated through the treating zone.

40 Further objects and advantages of the invention will be apparent to those skilled in the art from the following detailed description taken in connection with the accompanying drawing in which

45 Fig. 1 is a diagrammatic view partly in section of an apparatus particularly adapted to carry out the process of the present invention.

50 Fig. 2 is a diagrammatic view partly in section of a modified form of apparatus of the invention, in which the improved process may be carried out.

Referring to Fig. 1 of the drawing, the invention is illustrated by describing the treatment of a cracked gasoline or naphtha with a filtering or decolorizing clay such as fuller's earth.

The clay and oil mixture is introduced into the system through a pipe 2 as a slurry and forced by means of a pump 4 through a conduit 6 connecting with pipe coils 8 mounted in a pipe still furnace 10. The oil-clay mixture in passing through the coils 8 is heated to a temperature sufficiently high to vaporize substantially all of the oil constituents. If necessary a pressure may be maintained sufficiently high to retain substantially all of the oil constituents in liquid phase in the coils 8. In most cases however, the oil is permitted to vaporize in the coils. Heated oil-clay mixture is conducted from the pipe still furnace 10 through a valved transfer line 12 and introduced into a flash or vapor separating chamber 14 comprising the lower portion of a fractionating tower 16. In order to facilitate the substantially complete removal of hydrocarbon vapors from the clay settling out in chamber 14, superheated steam may be introduced through a distributor 18, but the velocity of steam should not be so great as to prevent settling out of the clay. The amount of steam is also controlled for the purpose of regulating the oil content of the clay.

30 The gasoline or naphtha vapors separated in chamber 14 are conducted through a vapor outlet 20 into the upper part of the fractionating tower 16 where the vapors are rectified in accordance with the usual practice to give a final gasoline product having the desired end boiling point. The heavy ends of the crude gasoline are con- 35

30 densed in tower 16 and withdrawn through a line 21 into a steam stripper column 22, in which the light constituents are removed with steam and passed through a vapor line 23 into tower 16. The bottoms in column 22 are passed to storage 40 through a valved line 24. The overhead gasoline vapors are conducted from tower 16 through a vapor line 26 and condensed in condensers 28. The resulting condensate, which contains water

45 because of the use of superheated steam in chamber 14 and column 22, is withdrawn into a water separator 29 in which the water is separated and withdrawn through a line 30. Gasoline and gas are passed from separator 29 into a receiver 31. Gas is vented from receiver 31 through a valved line 32 and gasoline passed to storage through a valved line 34. In conducting the fractionation in the tower 16, it is of particular advantage to return a portion of the finished gasoline from receiver 31 to the upper plates of the tower, and 50

this may be accomplished by the use of a line 36 in which is mounted a pump 38.

The used clay separated out in the lower part of chamber 14 is removed therefrom by means of a rotary feed valve 40 and passed through a line 42 into an injector 44 mounted in a transfer line 46. Hot gas is supplied to the line 46 and injector 44 by a pump 48, and to this gas may be added preheated air supplied from a line 50 and forced 10 by means of a pump 52 through a line 54 and a preheating coil 56 into the line 46.

The ratio of contact clay to be revivified, to hot gas delivered to injector 44 may be adjusted by regulating the speed of rotary feed valve 40 15 in relation to the volume of gas passed into the injector 44. The proportion of clay should be properly adjusted so that it can be readily carried in suspension or conveyed by the gas mixture. The clay-gas mixture is forced, at a con- 20 siderable velocity from the injector 44 through the line 46 and passed through a series of coil sections 58 mounted in a furnace 60. The temperature of the mixture is preferably raised in the first coil section to a temperature at which 25 oxidation starts or an exothermic reaction begins to take place. This reaction is continued throughout the remainder of the coil sections by the heat of the furnace 60 and/or by the introduction of regulated quantities of oxygen or air 30 through valved branch lines 62 which are supplied with air from line 54 through connecting line 64.

The temperature in the clay-gas mixture passing through the coil sections mounted in the furnace 60 is preferably controlled so that fusion of 35 the clay particles is avoided and proper revivification effected. This is accomplished by controlling the furnace temperature and particularly the quantity of air introduced through lines 62 and/or coil 56. The coil sections 58 are provided with thermocouples 66 which may be connected to recording instruments or to suitable 40 automatic control apparatus to automatically regulate the quantity of air introduced through coil 56 and lines 62. The electrical mechanism 45 for effecting such automatic control is common in various arts and therefore is not shown in detail. If automatic control is desired, all that is necessary is to provide means for automatically regulating the supply of air to the various coil sections in response to variations in temperature in 50 the coil sections as recorded by thermocouples 66.

The clay-gas mixture is conducted from the last coil section 58 through a transfer line 68 into a centrifugal dust separator 70 in which the re- 55 vivified clay is separated from the gas. The re-vivified clay is removed from separator 70 by means of a sealed rotary valve 72 similar to valve 40, while the hot gas is conducted through an exhaust line 74. The circulating gas introduced 60 into injector 44 by pump 48 is drawn from exhaust line 74 through a connecting line 76 while the excess gas is conducted from the line 74 into the lower part of a bag dust separator 78 in which heat exchange coil 56 is mounted. The hot gases 65 from line 74 pass in heat exchange with air conducted through coil 56.

The bag dust separator 78 is provided with a plurality of bag units 80 mounted above the coil 56. Each of these bag units includes a plurality 70 of fabric bags 82 supported by a movable rack 84. The hot gas introduced from the pipe 74 naturally contains small amounts of very fine dust which is filtered out in the bags 82 since the gas passes upwardly through the bags, leaving the 75 dust inside. The cleaned gas is withdrawn

through individual valved conduits 86 into an exhaust line 88. After one set of bags has been in operation for a desired length of time, the outlet valve in the conduit 86 from that unit is closed and the valve in the outlet of another unit 5 is opened, to permit shaking of the bags in the closed unit. The dust shaken from the bags is discharged into the lower part of the separator 78, and removed by means of a rotary valve 90 which is constructed like valve 40. Instead of 10 using the bag dust separator an electrical precipitator may be used for coagulating the dust particles in the exhaust gas.

The apparatus shown in Fig. 2 contains substantially the same elements or element equivalents as the revivifying part of the apparatus shown in Fig. 1. The contact clay or other filtering medium from a process such as shown in Fig. 1, and which is to be revivified, is introduced into the system through the rotary feed valve 40 15 and conducted through line 42 and injector 44 into a stream of hot gas in line 46. As in Fig. 1, the spent gas produced in the system is passed into line 46 by means of pump 48. The mixture of hot gas and finely divided filtering agent is discharged into the upper portion of a reaction tower 53 and allowed to settle therethrough while the reaction is being carried on. Air or oxygen is supplied for the revivification in tower 53 by drawing air through pipe 50 and forcing it by 20 means of a pump 52 through a valved line 54 and a heat exchanger 79 into a combustion chamber 25 55 through connecting lines 57, 59 and 61. Gas from line 63 is burned in the lower part of the combustion chamber 55 in a burner 65 for the 30 purpose of heating the air to the desired temperature. Air for the burner 65 is drawn from line 59. The products of combustion from chamber 55, and introduced air, are mixed together and conducted through a valved line 67 into the line 46 35 40 in advance of the injector 44. Valved branch lines 69 are also provided for the introduction of the hot gaseous mixture into various parts of the reaction tower 53.

The control of the temperature of the gases 45 passing through the line 67 may be accomplished by varying the amount of air introduced into the combustion chamber through the line 61 or by varying the preheat of the air thus introduced by directing any part of the air around the heat 50 exchanger 79 through valved bypass line 59, or by varying the combustion of burner 65. In the 55 normal operation of the apparatus shown in Fig. 2 the temperature in the tower 53 may be controlled in response to variations in the readings from thermocouples 66. The gas mixture passed into the injector 44 is preferably at a sufficient 60 temperature to bring the contact clay up to the reaction temperature. Heat and oxygen are thereafter supplied to the reacting materials 65 through the branch lines 69. The revivified clay or other contact material suspended in the gas is conducted from tower 53 through the transfer line 68 into a centrifugal separator 70 from which the revivified clay is discharged through a 70 rotary valve 72. The hot exhaust gases pass from the separator 70 through a valved line 74 and in heat exchange with the air passed through heat exchanger 79. The recycle gas used in the process is withdrawn from the line 74 through a line 76 by the pump 48. The type of dust separator 78 shown in Fig. 1 may be used instead of heat exchanger 79 and/or an electrical precipitator may be used.

The finely divided clay and other materials to 75

be revivified in accordance with the process of the present invention usually contain small amounts of adsorbed hydrocarbons so that some oxygen is used up in the combustion of these materials during the early part of the revivification operation. Oxygen is also used in the oxidation of adsorbed sulphur and in the oxidation of inorganic materials reduced by the oil treating process. The exhaust gases from the process therefore contain a relatively larger proportion of nitrogen and small proportions of carbon dioxide and water vapor. Traces of other gases such as sulphur dioxide are also present.

The proportion of oil or hydrocarbon constituents left in the clay to be treated has an important effect on the revivification operation and it is therefore necessary to properly control the "drying" of the clay as it is separated from the vapors in chamber 14. Some combustible material should be left in the clay to aid in controlling the temperature and oxidation, but an excess sufficient to give a fusion temperature must be avoided. In some cases preheated air may be used without recirculating exhaust gases.

25 The process is applicable to the treatment of finely divided clay used in any process of oil refining, but it is to be understood that the clay before being introduced into the revivification operation is to be substantially free of heavy hydrocarbons. Clays used in the contact filtration of lubricating oil stocks are preferably washed with a solvent such as gasoline, butane or propane prior to being revivified.

In describing the process as carried out in the apparatus disclosed in the drawing reference has been more particularly made to the revivification of contact clays, but it is to be understood that the invention is equally applicable to the revivification of silicates, oxides and other inorganic refining agents or mixtures thereof. Metallic oxides either alone or when mixed with clays or silicates may be readily revivified by the process of the present invention, since the oxidation may be controlled accurately. In treating various types of materials, it is to be understood that different temperatures may be required in order to convert the material into its original or desired form. Some clays or oxides or mixtures thereof may require relatively large amounts of oxygen and high or low temperatures for revivification, whereas other materials may require only a relatively small amount of oxygen and relatively high or low temperatures.

Having thus described the invention, what is claimed as new is:

1. The process of revivifying and reactivating used solid inorganic refining agents, which comprises passing a rapidly flowing stream of carrier gas through a heating zone in contact with an extensive heating surface, introducing into said stream entering said zone a stream of the finely divided agent to be revivified whereby said agent is passed with said gas through said heating zone, adding oxygen to said gas in said zone at a plurality of points to control the oxidation and revivification of the agent passing therethrough, discharging the stream of gas and agent into a separating zone in which the agent is precipitated from the gas, and returning a part of the gas to the reaction zone as a carrier medium for the agent being conducted thereto.

2. An apparatus for treating solid adsorbent, which comprises a mixer for intimately mixing comminuted solid adsorbent with a carrier gas, a tubular heating element having an extensive

heating surface, means for passing the mixture of gas and solid adsorbent through said heating element in a continuous stream, means for supplying air to said mixer, means for supplying air to said tubular element at a plurality of points 5 therewith to mix with the stream of gas and adsorbent passing therethrough, means for supplying heat to the material passing through said tubular element said means including means for externally heating the tubular heating element, 10 and means for separating solid adsorbent from gas after passage of the mixture through said tubular heating element.

3. The apparatus as defined by claim 2 in which means is provided for recirculating through the apparatus a portion of the gas separated from the treated solid adsorbent.

4. The process of refining solid treating agents, which comprises passing a carrier gas in a rapidly flowing stream of restricted cross-section through 20 a heating zone in contact with an extensive heating surface, introducing into and suspending in the said gas stream entering said zone a stream of the finely divided agent to be refined and passing said agent with said gas through and out of 25 said heating zone, adding oxygen to said mixture of gas and suspended agent passing through said zone at a plurality of points to control the oxidation and refining reactions taking place in said zone, and discharging the stream of gas and agent 30 from said heating zone into a separating zone in which the refined agent is separated from the gas.

5. The process of refining solid treating agents of the type of fuller's earth, charcoal, clays and silicates, which comprises passing a rapidly flowing stream of a carrier gas through a heating zone in contact with an extensive heating surface, introducing into and suspending in said gas stream entering said zone a stream of the finely divided agent to be treated and passing the agent 40 in suspension in said gas through said heating zone, controlling the application of heat to said heating surface to regulate and control the temperature to which the gas and agent mixture is heated, introducing oxygen into said gas mixture 45 in said heating zone at a plurality of points to control the refining of the agent passing therethrough, discharging the stream of gas and refined agent from said heating zone into a separating zone in which the agent is separated from 50 the gas.

6. The process of refining solid treating agents which comprises passing a carrier gas containing free oxygen in a rapidly flowing stream through an externally heated coil of restricted cross-section relative to its length, introducing into and suspending in said gas stream passing to the inlet of said coil a stream of the finely divided treating agent to be refined and passing said agent in suspension in said gas stream through 55 and out of said coil, controlling the application of heat to said coil to regulate and control the temperature to which the gas and agent mixture is heated therein to control the refining of the agent passing therethrough, further aiding in the control of the refining of said agent passing through said coil by introducing oxygen into the mixture of gas and agent at an intermediate point in said coil, discharging the stream of gas and agent in suspension therein together from said coil after 60 completing the refining of said agent and passing the same into a separating zone in which the refined agent is separated from the resulting gas.
